UNITED STATES PATENT OFFICE

LEONARD LESLIE HALES, OF WINNIPEG, MANITOBA, CANADA

BRUSH

Application filed September 27, 1929, Serial No. 395,555, and in Canada June 14, 1929.

My invention relates to brushes having particular reference to clothes brushes and the like but not restricted in its application thereto.

5 In the use of brushes and similar devices for cleaning cloth or clothing of various kinds or more generally in cleaning articles of any kind by a brushing operation a considerable percentage of the dirt, lint and 10 other foreign substances adhering to the article to be cleaned is transferred to and adheres to the bristles of the brush during the cleaning operation so that upon the commencement of each stroke of the brushing 15 action part of such adhering substances is brought back into contact with the article to be cleaned.

In addition cloth or fabrics with a nap or pile when subjected to a pressure in the 20 brushing operation by the use of a stiff unyielding brush suffer damage, essentially so in brushing delicate fabrics where a light touch is essential to the preservation and care of the fabric, and one of the objects of the 25 present invention is to provide a brush with a yielding action less injurious to the fabric being cleaned and terminating in a vibratory movement of increased velocity at the conclusion of each actuation of the brush to automatically cleanse the bristles of adhering 30 foreign substances and to carry out such dislodgment in a direction away from the article being cleaned.

A further object of my invention is to provide a brush of such a character convertible where required by means of a locking attachment into a non-yielding ordinary form of brush.

40 A still further object of my invention is to provide a brush of such a character of simple economical construction, easy of operation and less laborious to wield than the ordinary form of brush and adapted to be manufactured in a variety of forms for use in brushing operations of various kinds.

With the above and other objects in view my invention resides in the combination of parts hereinafter designated and claimed in the appended claims reference also being had to the accompanying drawings wherein like 50 characters of reference are used to indicate like parts throughout the several views and wherein:

Fig. 1 is a side elevation partly in section of the device assembled illustrated with the 55 locking device disengaged.

Fig. 2 is a top plan view of the device assembled illustrated partly in section.

Fig. 3 is a fragmentary detail sectional elevation of a part of the operating mechanism illustrating the operation of the locking device and showing same disengaged.

Fig. 4 is a similar view showing the locking device engaged.

Fig. 5 is a top plan view of the spring engaging cap.

Fig. 6 is a side view of same.

Fig. 7 is a sectional view of the plate illustrated as taken on a line 7—7 of Fig. 2.

Referring to the drawings 1 indicates a 70 brush base to which would be secured bristles 2. The brush proper would not be restricted to any particular form or shape the construction depending on the use to which it would be put.

75 Secured to the back of the base 1 is a shank 3 which is flattened at its forward extremity and forwardly secured to the base 1 by means of screws 4. The shank 3 is further intermediately secured to the rear of the base 1 by a clamp 5 shaped to partially encircle the said shank and attached to the base 1 by screws 6. The said shank 3 extends beyond the brush and has secured to the extremity thereof, seated in a suitable slotted opening provided therein, a spring 7 which preferably takes the form of a flat steel spring though not necessarily restricted thereto.

80 The operative handle attachment for the device consists of a hand grip 8 centrally pro-

vided with a cylindrical bore 9 and has secured thereto a tubular sleeve or ferrule 10 by means of screws 11. The said sleeve 10 is adapted to receive the shank 3 and provide 5 a bearing therefor and is engaged therewith by a screw 12 secured in a suitable threaded opening in the shank 3 and operating in a slotted groove 13 provided in the sleeve 10 adjacent the inner extremity thereof, the said 10 screw 12 sliding in the groove 13 and permitting of a partial rotation of the said shank within the said sleeve 10.

Provided in the shank 3 is a slotted opening 14 for engagement of the locking device 15 which consists of a lever or catch 15 transversely mounted on a pin 16 which is mounted to rotate in a transverse slot provided therefor in the sleeve 10, the said slot being bisected by a slotted opening 18 in the said 20 sleeve aligned with the opening 14 in the shank 3.

A plate 19 provided centrally with a suitable opening 20 for operation of the catch 15 is secured to the sleeve 10 by means of 5 screws 21 received in suitable threaded openings provided therefor in the said sleeve. The under face of the plate 19 is indented or recessed as indicated at 22 to provide, in conjunction with the transverse slot in the 10 sleeve 10, a bearing for the pin 16. The bearing so provided for the pin 16 is of a sufficiently close or snug fit for the said pin as to retain the catch 15 in any set position within the limits of movement permitted it, such 15 fit being partially secured by the plate 19 being made of a sufficiently resilient material as to insure a constant moderate pressure thereby on the said pin 16 when the attaching screws 21 are tightened in place. In 20 consequence application of pressure to the catch 15 would be necessary for its operation preventing accidental engagement of the said catch.

The outer extremity of the spring 7 is received in a slotted opening 23 provided in a cap 24 which is secured to the extremity of the hand grip 8 by a screw 25 inserted through an elongated opening 26 in the head of the cap 24 and screwed into the grip 8. 25 This permits of partial rotation of the cap 8 for adjustment of the tension of the spring 7. A slot 27 in the head of the cap for reception of a screw driver or similar instrument facilitates adjustment of the said cap.

50 In the operation of the device when the locking lever is disengaged application of the brush to the fabric to be cleaned and movement thereof in a brushing operation serves by reason of the partial adherence of the 55 bristles to the fabric to rotate the shank 3 in the sleeve 10 to the extent permitted by the operation of the engaging screw 12 in the slotted opening 13. Such partial rotation of the said shank has the effect of applying a 60 torsional tension to the spring 7. Upon com-

pletion of the brushing movement and disengagement of the bristles from the fabric the spring 7 actuates the shank 3 imparting a reverse rotation thereto of considerable velocity terminating in a sharp reversal at the 70 conclusion thereof with accompanying vibration by the action of the spring in adjustment of the shank to its normal position. This action has the effect of dislodgment of 75 adhering substances from the bristles of the brush, the initial and chief dislodgment taking place in the direction of brushing movement and in consequence away from the fabric being cleaned. This rotation and vibration is of such rapidity as to permit of 80 an almost immediate re-application of the brush without appreciable delay.

Adjustment of the tension of the spring 7 can be secured by loosening the screw 25 in the cap 24 and rotation of the cap the desired amount the screw 25 operating in the slot 23 provided therefor, the said screw being re-tightened upon completion of the adjustment.

Where it is desired to use the brush as an 90 unyielding ordinary form of brush for any reason the locking lever 15 is engaged in the slot 14 provided in the shank 3 preventing rotation of the shank. In the event of breakage of the spring or other part such locking 95 engagement of the shank could be made to permit of continued use of the brush as an ordinary unyielding device until repairs could be effected.

The device could be re-adjusted for use in 100 a variety of forms to accommodate various kinds of brushes for various uses where such an actuated brush would be advantageous including furniture and carpet cleaning devices, without departure from the spirit of my invention and such re-adaptation would necessarily be considered as within the scope of 105 the present invention.

Having thus described my invention what I claim is:—

1. The combination with a brush of a shank secured to said brush, a sleeve rotatably mounted on said shank having a laterally disposed slot adjacent the inner extremity thereof, a set screw on said shank slidably engaging in said slot, a handle on said sleeve and a spring on said shank engaged by said handle and arranged to normally maintain said shank with the set screw intermediately disposed in the slot in said sleeve.

2. The combination with a brush of a shank secured to said brush, a sleeve wherein said shank is rotatably mounted having a laterally disposed slot adjacent the inner extremity thereof, a set screw on said shank engaging said slot, a handle on said sleeve provided with a central bore, a flat spring seated in the extremity of said shank extending therefrom and disposed in said bore and a cap on 130

the extremity of said handle engaging said spring.

3. The combination of a brush, a shank secured to said brush, a sleeve rotatably mounted on said shank having a laterally disposed slot adjacent the inner extremity thereof, a set screw on said shank engaging said slot, a handle on said sleeve provided with a central bore, a spring secured to the extremity of said shank and disposed in said bore, a cap on the extremity of said handle engaging said spring and means for adjustment of said cap to vary the tension of said spring.
